123,635

DESIGN FOR A DISPLAY CARTON OR SIMILAR ARTICLE

Virginia H. Crate, Syracuse, N. Y., assignor to Regal Paper Company, Inc., Pulaski, N. Y., a corporation of New York

Application September 10, 1940, Serial No. 94,921

Term of patent 14 years

To all whom it may concern:

Be it known that I, Virginia H. Crate, a citizen of the United States of America, residing in the city of Syracuse, county of Onondaga and State of New York, have invented a new, original, and ornamental Design for a Display Carton or Similar Article, of which the following is a specification, reference being had to the accompanying drawing, forming part thereof.

Figure 2 is a front elevation showing in detail the decoration (both front and back are the same).

I claim:

The ornamental design for a display carton or similar article, substantially as shown and described.

VIRGINIA H. CRATE.
